UNITED STATES PATENT OFFICE.

HEINRICH MUNDLOS, OF MAGDEBURG-NEUSTADT, GERMANY.

SHUTTLE-RACE FOR SEWING-MACHINES.

SPECIFICATION forming part of Letters Patent No. 759,298, dated May 10, 1904.

Application filed June 25, 1902. Serial No. 113,153. (No model.)

To all whom it may concern:

Be it known that I, HEINRICH MUNDLOS, a subject of the King of Prussia, German Emperor, and a resident of Magdeburg-Neustadt, in the Kingdom of Prussia, German Empire, have invented certain new and useful Improvements in Covers for the Races of Sewing-Machine Shuttles, of which the following is a specification.

10 My invention relates to improvements in covers for the races of sewing-machine shuttles, and more especially for the races of sewing-machines with a shuttle oscillating in a circle. In these shuttles it has always been 15 a great disadvantage that if the thread was torn the torn-off end of the thread was held fast between the shuttle and the race, whereby the sewing-machine was stopped and could only be started again after opening the cover 20 of the race, removing the shuttle, arranging the thread, and setting the shuttle in again. All sewing-machines with circular races possess this drawback, which is done away with by the construction of the cover forming the 25 object of the present invention, and represented in the accompanying drawings, in which—

Figure 1 is a section of a race the cover of 30 which is provided with my new arrangement. Fig. 2 is an upper view of the race. Fig. 3 is a lower view of the cover; and Fig. 4 is a vertical section of the race, showing a special construction of the shuttle.

I attain the purpose of the invention by arranging one or several grooves or slots of any 35 convenient form in the cover for the race in that way that in case the thread is torn the torn-off end will be situated into these grooves or slots—*i. e.*, will be pressed into the same by 40 means of the shuttle.

It will be understood that the invention may be employed for all suitable constructions of sewing-machines, the drawings only representing an example.

45 In the construction shown a ring *a* is connected, by means of arms *b*, with the nave *c* of the shuttle-race. To the ring *a* the circular cover *d* is fixed by means of screws or the like. The cover *d*, in connection with the

ring *a*, forms the guide for the shuttle *e*. On 50 the inside of the cover *d* an annular groove *f* is provided. It will be clear that this groove may have any convenient form, the same fulfilling only the purpose of forming the space taking up the torn-off threads. On the lower 55 side of the cover a cut-out *g* is provided, which serves the purpose of allowing the torn-off threads to fall out. Instead of the annular groove slots may be provided, which allow the thread to immediately fall out. 60

In the construction shown in Fig. 4 it is shown that the purpose of the invention can also be attained by a special construction of the shuttle. In the construction shown the edges of the shuttle are chamfered, as shown 65 at *g'*, whereby it is attained that the torn-off thread can also be pressed into the small triangular spaces at the top and bottom of the shuttle. It will be clear that by chamfering the edges of the shuttle the purpose of the 70 invention can be attained alone; but advantageously this construction is used in combination with a special construction of the cover *d*.

Having thus fully described the nature of this invention, what I desire to secure by Letters Patent of the United States is—

1. The combination, in a shuttle-race for sewing-machines, of a shuttle with a race-cover consisting of an annular plate provided with a groove at the inside passing around 80 the inner edge of the plate, substantially as described and for the purpose indicated.

2. In a shuttle-race for sewing-machines, the combination of a shuttle with a race-cover comprising an annular plate provided with a 85 circular groove at its inside passing around the inner edge of the plate and further provided with holes connecting the groove with the outside of the plate, essentially as described and shown.

In testimony whereof I have signed my name to this specification in the presence of two subscribing witnesses.

HEINRICH MUNDLOS.
